ABSTRACT

A pair of output signals of equal magnitude and opposite phase are developed in response to the application of a single input signal. The output signals ride upon an output bias voltage which may be made to equal approximately one-half of an applied supply voltage.

PHASE SPLITTER CIRCUIT

This invention relates to a phase splitter circuit which is responsive to the application of an input signal to develop a pair of output signals of equal magnitude and opposite phase.

Ordinarily, the output signals of a phase splitter circuit are applied to drive a class B push-pull amplifier circuit or the like. In order to maximize the linear voltage swing of the driven circuit, it is desirable that the output signals of the phase splitter circuit ride upon an output bias voltage which is approximately equal to one-half of the applied supply voltage. The present invention provides a simple phase splitter circuit which is capable of achieving this desired result and which is suitable for fabrication as an integrated circuit or as a discrete circuit.

According to the invention, a phase splitter circuit includes identical left and right phase splitter networks as follows: A first transistor includes a base electrode connected to an input node, an emitter electrode connected to a feedback node, and a collector electrode connected to a load node. A second transistor includes a base electrode connected to the load node, an emitter electrode connected to an output node, and a collector electrode connected to a supply node. A third transistor includes a base electrode connected to a bias node, a collector electrode connected to the feedback node, and an emitter electrode. A first resistor is connected between the supply node and the load node. A second resistor is connected between the output node and the bias node. A third resistor is connected between the emitter electrode of the third transistor and a reference node. The series combination of a diode and a fourth resistor is connected between the bias node and the reference node. A fifth resistor is connected between the feedback nodes of the left and right networks.

As a result, in response to the application of an input signal E_i between one of the left and right input nodes and the reference node when a suitable input bias voltage V_{b_i} is applied between each of the input nodes and the reference node, left and right output signals E_{of} and E_{or} are developed between corresponding ones of the left and right output nodes and the reference node such that the left and right output signals E_{of} and E_{or} ride upon an output bias voltage V_{b_o} which is approximately defined by the following equation:

$$V_{b_o} = \frac{V_s - V_{j_2} + \left[\frac{R_1}{R_3} \right] V_{j_3} - \left[\frac{R_2}{R_3} \right] \left[\frac{R_1}{R_2 + R_4} \right] V_{j_4}}{1 + \left[\frac{R_1}{R_2 + R_4} \right] \left[\frac{R_4}{R_3} \right]}$$

and such that the gain E_{of}/E_i and E_{or}/E_i of the phase splitter circuit is approximately defined by the following equation:

$$\frac{E_{of}}{E_i} = - \frac{E_{or}}{E_i} = \frac{R_1}{2R_3}$$

where V_s is a supply voltage applied between the supply node and the reference node; V_{j_2} and V_{j_3} are the characteristic base-emitter junction voltage drops of the second and third transistors, respectively; V_{j_4} is the characteristic anode-cathode junction voltage drop of the diode; and R_1 , R_2 , R_3 , R_4 and R_5 are the resistance

values of the first, second, third, fourth and fifth resistors, respectively.

Provided that the following criteria are satisfied:

$$\begin{aligned} V_{j_2} &= V_{j_3} = V_{j_4} \\ R_1 &= R_2 + R_4 \\ R_3 &= R_4 \end{aligned}$$

the output bias voltage V_{b_o} is approximately defined by the following simplified equation:

$$V_{b_o} = V_s/2$$

10 which indicates that the output bias voltage V_{b_o} is equal to one-half of the supply voltage V_s . Each of the above three criteria may be readily met whether the phase splitter circuit is fabricated as an integrated circuit or as a discrete circuit.

15 These and other aspects and advantages of the invention may be best understood by reference to the following detailed description of a preferred embodiment when taken in conjunction with the accompanying drawing.

20 In the drawing, the sole FIGURE is a schematic diagram of a phase splitter circuit incorporating the principles of the invention.

25 Referring to the drawing, a phase splitter circuit 10 includes a supply node 12 and a grounded reference node 14 across which a supply voltage V_s is applied. The phase splitter circuit 10 includes identical left and right phase splitter networks 16, and 16_r.

30 In the left phase splitter network 16_f, a first transistor 18_f includes a base electrode connected directly to an input node 20_f, a collector electrode connected directly to a load node 22_f, and an emitter electrode connected directly to a feedback node 24_f. A second transistor 26_f includes a base electrode connected directly to the load node 22_f, a collector electrode connected directly to the supply node 12, and an emitter electrode connected directly to an output node 28_f. A third transistor 30_f includes a base electrode connected directly to a bias node 32_f and a collector electrode connected directly to the feedback node 24_f. The transistor 30_f also includes an emitter electrode. A fourth transistor 34_f includes a base electrode and a collector electrode both connected directly to the bias node 32_f. The transistor 34_f also includes an emitter electrode.

35 Further, in the left phase splitter network 16_f, a first resistor 36_f is connected between the supply node 12 and the load node 22_f. A second resistor 38_f is connected between the output node 28_f and the bias node 32_f. A third resistor 40_f is connected between the emitter electrode of the third transistor 30_f and the reference node 14. A fourth resistor 42_f is connected between the emitter electrode of the fourth transistor 34_f and the reference node 14.

40 Since the right phase splitter network 16_r is identical to the left phase splitter network 16_f, like numerals are used to denote like elements except that the numerals designating elements in the right phase splitter network 16_r, have subscripts *r* while the numerals designating elements in the left phase splitter network 16_f, have subscripts *f*. In addition, a fifth resistor 44 is connected between the feedback node 24_f in the left network 16_f and the feedback node 24_r in the right network 16_r.

45 It will be noted that the left and right fourth transistors 34_f and 34_r are actually connected to function as diodes. In effect, the diode-connected transistors 34_f and 34_r have an anode electrode connected directly to a corresponding one of the left and right bias nodes 32_f and 32_r, and a cathode electrode connected to a corre-

sponding one of the left and right fourth resistors 42, and 42_r. Thus, where the illustrated phase splitter circuit 10 is to be fabricated as a discrete circuit, the devices 34_f and 34_r would be provided by ordinary diodes. However, for reasons which will be more fully explained later, the illustrated phase splitter circuit 10 is preferably fabricated as an integrated circuit. Accordingly, the devices 34_f and 34_r are depicted in the drawing in the "transistorized form" which has become conventional for the illustration of an integrated circuit diode.

A voltage divider network 46 is provided for applying a suitable input bias voltage V_{b_i} to the phase splitter circuit 10. The voltage divider network 46 comprises a first leg connected between the supply node 12 and a voltage divider node 48 and a second leg connected between the voltage divider node 48 and the reference node 14. The first voltage divider leg includes resistor 50, the base-emitter junction of transistor 52, and the base-emitter junction of transistor 54. The second voltage divider leg includes resistor 46 and the parallel connection of the base-emitter junction of transistor 58 and the base-emitter junction of the diode-connected transistor 60.

Preferably, the resistance of the resistor 50 is approximately twice the resistance of the resistor 56 so that the input bias voltage V_{b_i} defined between the voltage divider node 48 and the reference node 14 is about one-third of the supply voltage V_s applied between the supply node 12 and the reference node 14. A pair of resistors 62 and 64 apply the input bias voltage V_{b_i} from the voltage divider node 48 to the left and right input nodes 20_f and 20_r of the phase splitter circuit 10, respectively. It is to be understood that the precise form of the voltage divider network 46 is not of critical importance. Accordingly, the illustrated voltage divider network 46 may be replaced by virtually any network capable of generating the desired input bias voltage V_{b_i} .

Assuming that an input signal E_i having an increasing amplitude is applied between the left input node 20_f and the reference node 14 on top of the input bias voltage V_{b_i} , the conduction of current through the left first transistor 18_f and the left first resistor 36_f increases 45 thereby lowering the potential at the left load node 22_f. As the potential at the load node 22_f decreases, the conduction of current through the left second transistor 26_f decreases thereby decreasing the amplitude of the left output signal E_{of} defined between the left output node 28_f and the reference node 14. Thus, the left output signal E_{of} is out of phase with the input signal E_i .

The decrease in the potential at the left output node 28_f is coupled through the left second resistor 38_f to 55 lower the potential at the left bias node 32_f. As the potential at the bias node 32_f decreases, the conduction of current through the left diode 34_f and the left fourth resistor 42_f decreases thereby equally decreasing the conduction of current through the left third transistor 30_f and the left third resistor 40_f. With the conduction of current through the transistor 18_f increasing and the conduction of current through the transistor 30_f decreasing, the potential at the left feedback node 24_f rises to force a feedback current through the resistor 44 thereby raising the potential of the right feedback node 24_r.

As the potential at the right feedback node 24_r increases, the conduction of current through the right first transistor 18_r and the right first resistor 36_r decreases thereby raising the potential at the right load node 22_r. As the potential at the load node 22_r increases, the conduction of current through the right second transistor 26_r increases thereby increasing the amplitude of the right output signal E_{or} defined between the right output node 28_r and the reference node 14. Hence, the right output signal E_{or} is in phase with the input signal E_i .

The increase in the potential at the right output node 28_r is coupled through the right second resistor 38_r to raise the potential at the right bias node 32_r. As the potential at the bias node 32_r increases, the conduction of current through the right diode 34_r and the right fourth resistor 42_r increases thereby equally increasing the conduction of current through the right third transistor 30_r and the right third resistor 40_r. With the conduction of current through the transistor 18_r decreasing and the conduction of current through the transistor 30_r decreasing, the potential at the right feedback node 24_r is lowered to further increase the feedback current through the fifth resistor 44.

Through the foregoing analysis, it has been demonstrated that the application of an input signal E_i between the left input node 20_f and the reference node 14 results in the production of a left output signal E_{of} from between the left output node 28_f and the reference node 14 which is out of phase with the input signal E_i and results in the production of a right output signal E_{or} from between the right output node 28_r and the reference node 14 which is in phase with the input signal E_i . By a similar analysis, it may be demonstrated that the application of an input signal E_i between the right input node 20_r and the reference node 14 results in the production of a right output signal E_{or} from between the right output node 28_r and the reference node 14 which is out of phase with the input signal E_i and results in the production of a left output signal E_{of} from between the right output node 28_f and the reference node 14 which is in phase with the input signal E_i .

In either of the above events, it can be additionally demonstrated that the right and left output signals E_{of} and E_{or} ride upon an output bias voltage V_{b_o} which is approximately defined by the following equation:

$$V_{b_o} = \frac{V_s - V_{j_2} + \left[\frac{R_1}{R_3} \right] V_{j_3} - \left[\frac{R_2}{R_3} \right] \left[\frac{R_1}{R_2 + R_4} \right] V_{j_4}}{1 + \left[\frac{R_1}{R_2 + R_4} \right] \left[\frac{R_1}{R_3} \right]}$$

and that the gain E_{of}/E_i and E_{or}/E_i is generally defined by the following equation:

$$\frac{E_{of}}{E_i} = - \frac{E_{or}}{E_i} = \frac{R_1}{2R_5}$$

where V_s is the supply voltage applied between the supply node 12 and the reference node 14, V_{j_2} is the characteristic base-emitter junction voltage drop of the left and right second transistors 26_f and 26_r, V_{j_3} is the characteristic base-emitter junction voltage drop of the left and right third transistors 30_f and 30_r, V_{j_4} is the characteristic anode-cathode junction voltage drop of the left and right diodes 34_f and 34_r, R_1 is the resistance of the

left and right first resistors 36_f and 36_r, R₂ is the resistance of the left and right second resistors 38_f and 38_r, R₃ is the resistance of the left and right third resistors 40_f and 40_r, R₄ is the resistance of the left and right fourth resistors 42_f and 42_r, and R₅ is the resistance of the fifth resistor 44.

Where the following three criteria are satisfied:

- a. $V_{j_2} = V_{j_3} = V_{j_4}$
- b. $R_1 = R_2 + R_4$
- c. $R_3 = R_4$

equation (1) is simplified to the following equation:

$$3. V_{b_0} = V_s/2$$

which indicates that the output bias voltage V_{b_0} is equal to one-half of the supply voltage V_s . As previously pointed out, this is desirable where the left and right output signals E_{of} and E_{or} are to be applied to drive a Class B push-pull amplifier or the like. While each of the criteria (a), (b) and (c) can be met regardless whether the phase splitter circuit 10 is fabricated as an integrated circuit or as a discrete circuit, they are more readily satisfied when the circuit 10 is integrated.

The correctness of equation (3) may be quickly verified by analyzing the phase splitter circuit 10 with respect to bias voltages and currents only. Referring particularly to the left phase splitter network 16_f, it may be viewed as a voltage divider network having a first leg connected between the supply node 12 and the left output node 28_f, and having a second leg connected between the left output node 28_f and the reference node 14. Equation (3) is correct if the voltage drop across the first voltage divider leg between the supply node 12 and the left output node 28_f is equal to the voltage drop across the second voltage divider leg between the left output node 28_f and the reference node 14.

The first voltage divider leg includes the first resistor 36_f and the base-emitter junction of the second transistor 26_f. The second voltage divider leg includes a first branch connected between the left output node 28_f and the left bias node 32_f, and a second branch connected between the left bias node 32_f and the reference node 14. The first branch includes the second resistor 38_f only. The second branch includes parallel paths provided by the base-emitter junction of the third transistor 30_f and the third resistor 40_f, and provided by the anode-cathode junction of the diode 34_f and the fourth resistor 42_f.

Assuming that the criterion (a) is satisfied so that the base-emitter junction voltage drop V_{j_3} of the third transistor 30_f equals the anode-cathode junction voltage drop V_{j_4} of the diode 34_f, the current through the third and fourth resistors 40_f and 42_f is equal. Moreover, the current through the first resistor 36_f is equal to the current through the third resistor 40_f, while the current through the second resistor 38_f is equal to the current through the fourth resistor 42_f. Consequently, the current through each of the resistors 36_f, 38_f, 40_f, and 42_f is identical.

Assuming that the criterion (c) is satisfied, the resistance R₃ of the third resistor 40_f is equal to the resistance R₄ of the fourth resistor 42_f. Since the current through the third and fourth resistors 40_f and 42_f is equal, the voltage drop across the third resistor 40_f is equal to the voltage drop across the fourth resistor 42_f. As a result, the third transistor 30_f and the third resistor 40_f may be disregarded in computing the voltage drop across the second branch of the first voltage divider leg which is equal to the summation of the voltage drop V_{j_4}

across the anode-cathode junction of the diode 34_f and the voltage drop across the fourth resistor 42_f.

Assuming that the criterion (b) is satisfied, the resistance R₁ of the first resistor 36_f is equal to the summation of the resistance R₂ of the second resistor 38_f and the resistance R₄ of the fourth resistor 42_f. Since the current through the first, second and fourth resistors 36_f, 38_f and 42_f is equal, the voltage drop across the first resistor 36_f is equal to the summation of the voltage drop across the second resistor 38_f and the voltage drop across the fourth resistor 42_f.

The voltage drop across the first voltage divider leg between the supply node 12 and the left output node 28_f is equal to the summation of the voltage drop across the first resistor 36_f and the base-emitter junction voltage drop V_{j_2} of the second transistor 26_f. The voltage drop across the second voltage divider leg between the left output node 28_f and the reference node 14 is equal to the summation of the voltage drop across the second resistor 38_f, the anode-cathode junction voltage drop V_{j_4} of the diode 34_f, and the voltage drop across the fourth resistor 42_f.

Due to the satisfaction of the criterion (a), the voltage drop V_{j_2} across the base-emitter junction of the second transistor 26_f in the first voltage divider leg is equal to the voltage drop V_{j_4} across the anode-cathode junction of the diode 34_f in the second voltage divider leg. Further, due to the satisfaction of the criterion (b), the voltage drop across the first resistor 36_f is equal to the summation of the voltage drop across the second resistor 38_f and the voltage drop across the fourth resistor 42_f. Accordingly, the voltage drop across the first voltage divider leg between the supply node 12 and the left output node 28_f is equal to the voltage drop across the second voltage divider leg between the left output node 28_f and the reference 14. Thus, the validity of equation (3) is verified. A similar analysis may be made for the right phase splitter network 16_r.

It will now be appreciated that the illustrated embodiment of the inventive phase splitter circuit 10 is shown for demonstrative purposes only and that various alterations and modifications may be made to this preferred embodiment without departing from the spirit and scope of the invention.

What is claimed is:

1. A phase splitter circuit for developing left and right output signals E_{of} and E_{or} of equal magnitude and opposite phase between corresponding ones of left and right output nodes and a reference node in response to the application of a single input signal E_i between one of left and right input nodes and the reference node when a supply voltage V_s is applied between a supply node and the reference node and when a suitable input bias voltage V_{b_i} is applied between each of the left and right input nodes and the reference node, comprising: left and right first transistors each having a base electrode connected to a corresponding one of left and right input nodes, each having an emitter electrode connected to a corresponding one of left and right feedback nodes and each having a collector electrode connected to a corresponding one of left and right load nodes; left and right second transistors each having a base electrode connected to a corresponding one of the left and right load nodes, each having an emitter electrode connected to a corresponding one of left and right output nodes, each having a collector electrode connected to a single supply node, and each exhibiting

a characteristic base-emitter junction voltage V_{j_2} ; left and right third transistors each having a base electrode connected to a corresponding one of left and right bias nodes, each having a collector electrode connected to a corresponding one of the left and right feedback nodes, each having an emitter electrode, and each exhibiting a characteristic base-emitter junction voltage V_{j_3} ; left and right fourth transistors each having a base electrode connected to a corresponding one of the left and right bias nodes, each having a collector electrode connected to a corresponding one of the left and right bias nodes, each having an emitter electrode, and each exhibiting a characteristic base-emitter junction voltage V_{j_4} ; left and right first resistors each exhibiting a resistance R_1 and each connected between a corresponding one of the left and right load nodes and the supply node; left and right second resistors each exhibiting a resistance R_2 and each connected between a corresponding one of the left and right output nodes and a corresponding one of the left and right bias nodes; left and right third resistors each exhibiting a resistance R_3 and each connected between the emitter electrode of a corresponding one of the left and right third transistors and the reference node; left and right fourth resistors each exhibiting a resistance R_4 and each connected between the emitter electrode of a corresponding one of the left and right fourth transistors and the reference node; and a fifth resistor connected between the left and right feedback nodes; whereby the left and right output signals E_{of} and E_{or} ride upon an output bias voltage V_{b_0} which is equal to one-half of the supply voltage V_s when the following criteria are satisfied:

$$V_{j_2} = V_{j_3} = V_{j_4}$$

$$R_1 = R_2 + R_4$$

$$R_3 = R_4.$$

2. In combination: left and right first transistors each having base and emitter and collector electrodes, the base electrodes each connected to a corresponding one of left and right input nodes, the emitter electrodes each connected to a corresponding one of left and right feedback nodes, and the collector electrodes each connected to a corresponding one of left and right load nodes; left and right second transistors each having

base and emitter and collector electrodes and each exhibiting a characteristic base-emitter junction voltage V_{j_2} , the base electrodes each connected to a corresponding one of the left and right load nodes, the emitter electrodes each connected to a corresponding one of left and right output nodes, and the collector electrodes each connected to a single supply node; left and right third transistors each having base and emitter and collector electrodes and each exhibiting a characteristic base-emitter junction voltage V_{j_3} , the base electrodes each connected to a corresponding one of left and right diodes and the other of either the corresponding one of the left and right bias nodes or the reference node; and a fifth resistor connected between the left and right feedback nodes whereby left and right output signals E_{of} and E_{or} of equal amplitude and opposite phase are developed between corresponding ones of the left and right output nodes and the reference node in response to the application of an input signal E_i between one of the left and right input nodes and the reference node when a supply voltage V_s is applied between the supply node and reference node and when a suitable input bias voltage V_{b_i} is applied between the left and right output nodes and the reference node such that the left and right output signals E_{of} and E_{or} ride upon an output bias voltage V_{b_0} defined by the following equation:

$$V_{b_0} = \frac{V_s - V_{j_2} + \left[\frac{R_1}{R_3} \right] V_{j_3} - \left[\frac{R_2}{R_3} \right] \left[\frac{R_1}{R_2 + R_4} \right] V_{j_4}}{1 + \left[\frac{R_1}{R_2 + R_4} \right] \left[\frac{R_4}{R_3} \right]}$$

and such that the voltage gain E_{of}/E_i and E_{or}/E_i is defined by the following equation:

$$\frac{E_{of}}{E_i} = - \frac{E_{or}}{E_i} = \frac{R_1}{2R_3}.$$
